US00D902835S

(12) **United States Design Patent** (10) **Patent No.:** **US D902,835 S**
Badillo (45) **Date of Patent:** **** Nov. 24, 2020**

(54) **VEHICLE RACK**

(71) Applicant: **INTELLIGENT DESIGNS 2000 CORP.**, Aurora, CO (US)

(72) Inventor: **Paul Badillo**, Littleton, CO (US)

(73) Assignee: **INTELLIGENT DESIGNS 2000 CORP.**, Aurora, CO (US)

(**) Term: **15 Years**

(21) Appl. No.: **29/705,114**

(22) Filed: **Sep. 10, 2019**

Related U.S. Application Data

(63) Continuation of application No. 29/610,895, filed on Jul. 17, 2017, now Pat. No. Des. 859,284, which is a continuation of application No. 29/547,752, filed on Dec. 7, 2015, now Pat. No. Des. 793,947.

(74) Attorney, Agent, or Firm — Sheridan Ross P.C.

(57) **CLAIM**

The ornamental design for a vehicle rack, as shown and described.

DESCRIPTION

FIG. 1 is a perspective view of a vehicle rack;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a perspective view thereof interconnected to a vehicle;
FIG. 9 is a perspective view of a vehicle rack according to an alternate embodiment of the present disclosure;
FIG. 10 is a front elevation view of the vehicle rack according to FIG. 9;
FIG. 11 is a rear elevation view of the vehicle rack according to FIG. 9;
FIG. 12 is a right elevation view of the vehicle rack according to FIG. 9;
FIG. 13 is a left elevation view of the vehicle rack according to FIG. 9;
FIG. 14 is a top plan view of the vehicle rack according to FIG. 9;
FIG. 15 is a bottom plan view of the vehicle rack according to FIG. 9; and,
FIG. 16 is a perspective view of the vehicle rack according to FIG. 9 interconnected to a vehicle.
The broken lines depict unclaimed environmental subject matter and do not form any part of the claimed design.

1 Claim, 12 Drawing Sheets
